UNITED STATES PATENT OFFICE.

GEORGE E. HAYES, OF BUFFALO, NEW YORK.

IMPROVEMENT IN FASTENING COVERS TO VULCANIZING-FLASKS.

Specification forming part of Letters Patent No. 35,821, dated July 8, 1862.

To all whom it may concern:

Be it known that I, GEORGE E. HAYES, of Buffalo, in the county of Erie and State of New York, have invented a new and Improved Device for Fastening Down Covers to Vulcanizing-Vessels; and I do hereby declare that the following is a full, clear, and exact description of the same, reference being had to the accompanying drawings, forming part of this specification, in which—

Figure 1 represents a vertical central section of my invention. Fig. 2 is a plan or top view of the same.

Similar letters of reference indicate corresponding parts in the two figures.

The object of this invention is to facilitate the operation of fastening down the covers or heads on vulcanizing-vessels, such as are in general use by dentists for the purpose of vulcanizing india-rubber gums or sets of teeth.

The invention consists in the employment of two or more set-screws passing through a screw-ring, which screws on the upper edge of the cylindrical vulcanizing-vessel, and which bears down on the edge of the cover in such a manner that, by means of the set-screws acting in conjunction with the screw-ring, a perfectly steam-tight joint between the cover and cylinder is produced.

It consists, further, in the arrangement of a flange projecting from the lower surface of the cover beyond the packing in such a manner that said flange forms a correct guide for the cover and strengthens the top edge of the cylinder.

To enable those skilled in the art to make and use my invention, I will proceed to describe it with reference to the drawings.

Hitherto the covers of vulcanizing-vessels have been secured either with bolts and nuts, or else the cover has been screwed onto the cylinder itself by suitable male and female screw-threads. The bolts are liable to be twisted off by improper effort to tighten the joint when the packing has become imperfect. While, on the other hand, when the cover is made to screw onto the cylinder, the two surfaces, between which the packing is placed, moving in opposite directions, causes great friction and requires great power to render the joint tight; and, furthermore, it very soon wears out or dislodges the packing substance. These imperfections are overcome by my invention.

The cover A is provided with a groove, a, on its under surface to receive the packing-ring b, and it is placed loose on the top edge of the cylindrical vulcanizing-vessel B. The edge of this vessel is strengthened by a collar, c, which is rigidly attached to the same, and this collar is provided with a screw-thread, d, to screw into a ring, C, which resembles somewhat the ordinary screw-cover with the center turned out. If the cover A is in the proper position, the ring C is placed over it and screwed upon the screw-thread on the edge of the collar c until the under side of the ring strikes the top of the cover. The ring C is provided with two or more set screws, e, directly over the inner edge of the packing-groove a, and it requires but one or two turns of these screws to exert the desired pressure on the cover and to close the joint.

The cover A is provided with a flange, f, projecting from its under surface into the cylinder B. This flange serves to support the top edge of the cylinder, and said edge, when under pressure, is thus embraced between the collar outside and the flange inside, rendering it utterly impossible for the same to bend in, and separate from the collar. Without this flange the top edge of the cylinder, which is generally made of thin sheet-copper, is liable to knuckle in under a heavy pressure and high temperature, and the collar, together with the screw-ring, is blown off.

By the use of the screw-ring and set screws the joint can be made perfectly steam-tight, and when tight the cover will resist any pressure to which it may be exposed, and it will not be liable to be blown off.

Having thus described my invention, what I claim as new, and desire to secure by Letters Patent, is—

1. The arrangement of two or more set-screws, e, in combination with the screw-ring C, cover A, and cylinder B, as and for the purpose shown and described.

2. The projecting flange f, projecting from the under side of the cover A, and catching on the inside of the cylinder B, as and for the purpose specified.

GEO. E. HAYES.
